UNITED STATES PATENT OFFICE.

JULIUS T. KALWEIT AND WILLIAM H. GAULKE, OF MILWAUKEE, WISCONSIN, ASSIGNEES TO INDEPENDENT ELECTRIC MANUFACTURING COMPANY, A CORPORATION OF WISCONSIN.

SPEED-REGULATOR FOR ELECTRIC MOTORS.

1,001,647.

Specification of Letters Patent. Patented Aug. 29, 1911.

Application filed October 20, 1910. Serial No. 569,041.

To all whom it may concern:

Be it known that we, JULIUS T. KALWEIT and WILLIAM H. GAULKE, both of Milwaukee, Wisconsin, have invented a Speed-5 Regulator for Electric Motors, of which the following is a specification.

This invention consists of a speed regulator for electric motors having novel means for holding it electromagnetically at any 10 position of the contact-arm.

In general, our invention consists in providing an electromagnet which is energized by the circuit-current of the motor, and in conjunction therewith a sliding-bar which 15 is connected with the contact-arm of the rheostat, said sliding-bar having a series of notches corresponding to the several stops or points of the rheostat in position for several engagement with a tooth element when 20 the contact-arm is on the corresponding step or point; the notches being held in engagement with said tooth element by the attraction of the magnet and being released therefrom to permit the contact-arm to be 25 turned to the starting-point whenever the current ceases, as by opening the main-switch of the circuit.

In the preferred form of our invention, the sliding-bar is not directly attracted by 30 the magnet, but is actuated by the medium of a secondary bar which is directly attracted by the magnet and is operatively connected to the first bar by resilient means such as a spring.

35 Our invention further consists in the constructions and combinations which will be hereinafter described and specifically set forth in the claims.

For the better understanding of our invention, we have illustrated the same in 40 various embodiments in the accompanying drawings, wherein—

Figure 1 is a front elevation of a rheostat constructed in accordance with the most 45 improved form of our invention, and connected to a series motor; Fig. 2 is a side elevation of the front plate thereof, partly in section on the plane 2; Figs. 3 and 4 show other forms or embodiments of the essential 50 elements which may be used in place of the form used in Fig. 1, and Fig. 5 is a dia-grammatic view showing the method of connection for shunt-motors.

The reference letters refer each to the 55 same part in each figure of the drawings.

The rheostat as shown is of ordinary construction having a base-plate or front-plate *a* of suitable insulating material such as slate, marble, porcelain, etc., secured by screw *b* to the rheostat proper. On this 60 plate is mounted a post *c* which forms a pivot for the contact-arm *d*, which latter swings over an arc limited by stop-pins *e* and is provided with resilient contact-strips *f* and *g* making contact respectively with an 65 arcuate plate *h* and a series of disks or buttons *i* between which are connected the several lengths of resistance-wire, as commonly used in this type of apparatus. A coiled torsion-spring *j* is mounted in the hub of 70 the arm *d*, and being connected at one end to the pin *c* and at the other end to the hub of the arm *d*, acts to swing said arm into the starting position, shown in dotted lines in Fig. 1, when released. We have also 75 shown for purposes of illustration the usual terminal posts *k* together with the leads *l* of an electric circuit divided by a cutout switch *m*, and having the armature *x* of an electric motor in circuit therewith. As 80 thus far described the rheostat is of the ordinary and usual type, forming no part of our invention.

At one side of the arm *d* is mounted an electromagnet which consists of a coil *n* having a central core *o* and an L-shaped yoke *p* connected at one end with the end of the core *o*. Adjacent to this magnet is arranged an armature *Z* which is pivoted on a pin *z'*. Disposed to reciprocate in a direction at 90 right angles to the arm *d* is a sliding bar *q*, which is connected thereto by a link *q'* which is pivoted to the arm *d* upon a pin *d'*. Mounted above the bar *q* is a slotted post *R* carrying an adjustable edge bit *r'* which 95 may be adjusted and clamped in position by a set-screw *r*, and this bit is adapted to engage in one of a series of notches *q*² on the upper side of the arm *q*. The notches *q*² are preferably V-shaped, having their right-hand surfaces of the same angle as the corresponding face of the edge of the bit *r'*, and sufficiently steep to enable the bar to be held in engagement by means to be described. This means consists of a leaf- or 100 bar-spring *z*² which is secured to the armature *Z* by screws *z*³, said spring pressing the bar *q* upwardly against the edge of the bit *r'* as shown, whenever the magnet coil *n* is 105 energized so as to attract the armature *Z*. 110

The arm q is loosely guided so as to have a free vertical movement sufficient to enable the notches q^2 to engage with or clear the edge of the bit r' by means of a slotted post 5 q^3 , in the slot q^4 of which the bar q freely travels, and a pin q^5 which is placed below the opposite end of the bar.

The magnet-coil n is inserted between one of the terminals k and the rheostat-coils, as 10 shown, by the leads s , the opposite terminal k being permanently connected to the plate h and to the switch m through the motor x by leads l or in any other preferred manner. When the current is thrown on, the magnet 15 will attract the armature Z , and cause the spring z^2 to press the arm q against the bit r' . As the arm d is moved over toward the right by successive steps, the edge of the bit engages the successive notches q^2 , and the 20 strength of the magnet increases with the current, thus balancing the increasing force of the spring j . The angle of the notches q^2 and tooth p' is such that the attraction of the magnet is sufficient to hold the armature 25 in whatever notch it may engage in against the force of the spring j ; but as soon as the circuit is broken, as by opening the switch m , the attraction of the magnet ceases, and the armature, being no longer held thereby, 30 is released and allows the arm to be swung back to the starting-point by the spring j .

In Fig. 3 a somewhat simpler arrangement is shown, the pole-shoes t being in this case directly connected with the sliding bar 35 q which acts as its armature. The position of the bar q is reversed so that the notches q^2 come on the under side, and the magnet coil n is mounted on a core having two pole-shoes t , one of which has a tooth t' , which 40 takes the place of the bit r' . In this case the guiding-post q^3 and pin q^5 are dispensed with and a single pin p^2 substituted therefor. It will be seen that this acts in a similar manner with the form shown in Fig. 1, 45 the electromagnet in this case holding the bar-armature q directly in engagement with the tooth t' .

In Fig. 4 the arrangement is similar to the Fig. 3, except that the tooth t' is omitted 50 and an independent tooth u' mounted upon a separate member u substituted therefor. This leaves a small but constant air-break in the magnetic circuit which prevents the bar q from possible sticking from residual magnetism.

Fig. 5 illustrates the method of connection, as commonly used for shunt-motors. In this case three terminal-posts k are provided, two for the armature and one for the 60 field-current, the former being connected by leads l^2 to the contact-strip h and the extreme right-hand contact-button i , while the magnet-coil n is connected by leads s^2 to the third contact-post k and to the contact-button i in connection with the resistance-wire at the 65

other end of the resistance, as shown. The motor is represented by an armature v and field w , the former being connected in the usual manner by leads l' through the switch m to the first two terminal posts k , and the latter by lead y to the third terminal post k . 70

We wish it understood that our invention is not limited to the use of all the above described features and constructions, for some may be omitted and others may be varied or 75 modified in various ways, as will readily occur to those skilled in the art.

Having thus described our invention, what we claim as new and desire to secure by Letters Patent is:

1. In a regulator, the combination of a contact-arm, means for resiliently moving it into the starting position, an electromagnet, a sliding-bar guided to reciprocate in an endwise direction and having a plurality of notches on its upper side, an intermediate member connecting said bar with said arm, and a toothed member with which said notches are adapted to engage in the respective positions of said arm; said electromagnet being operatively connected with said arm and adapted when energized to hold said member in engagement with said notches. 85

2. In a regulator, the combination of a contact-arm, means for returning it when released to the starting position, a sliding-bar guided to reciprocate endwise and having some freedom of transverse movement, a link connecting said bar with said arm, a 100 fixed member opposite said bar, said bar and fixed member having a plurality of oblique interengaging surfaces which are adapted to become engaged when said bar is moved laterally to one side and to become 105 disengaged when the bar is moved laterally to the other side, and an electromagnet adapted when energized to move said bar laterally to the engaging side.

3. The combination of a movable contact-member, a fixed element, a member adapted to slide over said fixed element, a link connecting said last-named member with said contact-member, said sliding member and fixed element having interengaging surfaces oblique to the direction of movement of said sliding-member at points corresponding to different steps of the regulation, means adapted to return said movable contact-member to its starting position when released and to overcome the action of said interengaging surfaces when not otherwise held in engagement, and an electromagnet arranged to hold said interengaging surfaces in engagement, the weight of said 115 sliding member acting to withdraw it from engagement with said fixed element. 120

4. The combination of a movable contact-member, a fixed element, a member adapted to slide over said fixed element, means con- 125

necting said last-named member with said contact-member, said sliding member and fixed element having interengaging surfaces oblique to the direction of movement of said 5 sliding-member at points corresponding to different steps of the regulation, means adapted to return said movable contact-member to its starting position when released and to overcome the action of said interengaging surfaces when not otherwise held in 10 engagement, an electromagnet, an armature for said magnet, and a spring connected with said armature and actuated thereby to press said sliding-member against said fixed element 15 when said electromagnet is energized.

5. The combination of a movable contact-member, a fixed element, a member adapted to slide over said fixed element, means connecting said last-named member with said 20 contact-member, said sliding member and fixed element having interengaging surfaces oblique to the direction of movement of said sliding-member at points corresponding to different steps of the regulation, means 25 adapted to return said movable contact-member to its starting position when released and to overcome the action of said interengaging surfaces when not otherwise held in engagement, an electromagnet, a 30 pivoted armature for said electromagnet and a spring mounted on said armature and adapted when said armature is attracted to said magnet to press said sliding member against said fixed element.

6. In a regulator, the combination with a pivoted contact-arm, a sliding-bar guided to slide endwise and having a plurality of notches in one side and a certain lateral movement, a link connecting said bar with said arm, an edged bit on one side of said bar and adapted to engage in any of said notches, an electromagnet connected in circuit with the regulator, a pivoted armature for said electromagnet, and means yieldingly connecting said armature with said bar in such manner that when said armature is attracted said bar is pressed against said bit. 35 40 45

7. In a regulator, the combination with a pivoted contact-arm, a sliding-bar guided to slide endwise and having a plurality of notches in one side and a certain lateral movement, a link connecting said bar with said arm, an edged bit on one side of said bar and adapted to engage in any of said notches, an electromagnet connected in circuit with the regulator, a pivoted armature for said electromagnet, and a spring mounted on said armature and acting to press said bar laterally against said bit when said armature is attracted by said magnet. 50 55 60

In witness whereof we have hereunto set our hands in the presence of two witnesses.
